UNITED STATES PATENT OFFICE.

FISCHEL FISCHLOWITZ, OF ST. LOUIS, MISSOURI.

HOLDER FOR NECKTIES AND THE LIKE.

1,218,070.

Specification of Letters Patent.

Patented Mar. 6, 1917.

Application filed January 17, 1916. Serial No. 72,601.

To all whom it may concern:

Be it known that I, FISCHEL FISCHLOWITZ, a citizen of the United States, residing at the city of St. Louis, State of Missouri, have invented a certain new and useful Holder for Neckties and the like, of which the following is a specification, reference being had to the accompanying drawing, forming a part thereof.

10 This invention relates to a certain new and useful holder for neckties and the like, the principal object of my present invention being to provide a simple and inexpensive device adapted to hold and releasably secure 15 against accidental displacement or theft while displayed or exposed upon a counter or other support one or more neckties or the like.

With the above and other objects in view, 20 my present invention resides in certain novel features of form, construction, arrangement, and combination of parts, all as will herein-after be described and afterward pointed out in the claim.

25 In the accompanying drawing, which illustrates my invention in preferred form,—

Figure 1 is a perspective view of a holder for neckties and the like embodying my invention;

30 Fig. 2 is a plan view thereof;

Fig. 3 is a side elevational view of the same; and

Fig. 4 is a longitudinal sectional view thereof.

35 Referring to the said drawing, in which like reference characters refer to like parts throughout the several views, my new holder for neckties and the like, as there shown, comprises an elongated approximately rectangular flat base or bottom wall 1 and a pair of side walls 2—2 upstanding from base 1 at its opposite side edges. Base 1 projects forwardly some little distance beyond the front edges of side walls 2—2, and walls 40

45 2—2 have a downwardly and rearwardly inclined or sloping upper edge, walls 2—2 having greater height at their front than at their rear, edges. To obviate all sharp corners and at the same time attractively 50 crease the appearance of the holder, base 1 and walls 2—2 are preferably rounded at their corners, as shown.

55 At its rear end, base 1 is provided preferably integrally with an elongated extension 3, which is bent around as at 4 to project forwardly intermediate side walls 2—2 and

over and above base 1, this extension 3 forming or providing substantially a spring tongue yieldable vertically at its free end relatively to base 1. At its forward or free end, extension or tongue 3 is preferably provided with a downturned or tie-engaging lip 5.

Preferably adjacent their front edges, side walls 2—2 are provided with alining downwardly and rearwardly disposed slots 6—6, each of which slots at and along its rear wall is provided with a series of teeth or rack 7. Descriptively these slots 6—6 might hence be called rack-slots. The teeth of said 70 series may vary in number as desired, but preferably correspond in number with the number of ties or the like the particular holder is adapted or designed to hold; accordingly, the holder shown being adapted 75 or designed to hold six ties, six teeth in said series are shown.

Extending transversely across between side walls 2—2 and above tongue or extension 3, is a bar or the like 8 provided at its opposite 80 ends longitudinally with oppositely disposed headed extensions 9—9 which project through said slots 6—6 and are adapted to engage with the teeth of said racks 7.

By means of said bar 8 and its said teeth-engaging extensions 9, tongue 3 may be held or secured in adjusted position between walls 2—2, tongue 3 being yieldingly adjustable downwardly or upwardly relatively to base 1 depending upon the number of ties placed 90 within the holder. Accordingly, in use or practice, the tie or ties are preferably first doubled upon themselves and then at their neck-band portions in neat piles placed lengthwise within the holder between base 95 1 and tongue 3, tongue 3 being yieldingly adjusted to engage thereupon and being held in such adjusted position by its retaining bar 8, as illustrated in Fig. 4. Four ties 10 being shown, extensions 9 of bar 8 now preferably engage the fourth tooth, counting upwardly, of the series of teeth on the rack 7.

With tongue 3 so engaging upon the ties, it will be evident that, to remove one or more of the ties from the holder, a positive pull thereupon is required. However, one or more of the ties 10 being removed from the holder, either through pull thereupon as stated or otherwise, that is to say, with bar 8 first disengaged from said teeth to permit tongue 3 110 to yield upwardly, tongue 3 may again be lockingly engaged with the remaining ties

in the holder by easy manipulation downwardly of said bar 8—through slight pressure of the thumb or finger thereupon—to engage the proper teeth of said racks. All 5 said ties being removed from the holder and it being desired to again fill the holder, bar 8 may be readily disengaged, through pressure outwardly thereupon of the thumb or finger, from the lower teeth of the series, when, 10 under the resiliency of tongue 3, tongue 3 and bar 8 will move to uppermost position relatively to base 1, bar 8 in such movement sliding forwardly and upwardly on tongue 3. To facilitate such travel of bar 8, as well as 15 similar downward and rearward movement upon spring 3 of bar 8 in adjustments as described of spring 3, I preferably round the under surface of bar 8, as at 11.

While the holder here shown is adapted, 20 as stated, to contain or hold six ties, it will be obvious that by increasing the length of rack-slots 7, the height of walls 2 being also increased if necessary, the holder may be readily adapted to accommodate a larger 25 number of ties. It may be also here stated that base 1 has preferably a width sufficient to neatly accommodate between side walls 2 ties having neck-band portions of standard width; but it will also be understood that the 30 same may be of greater or less width, as may be desired, and that other changes in the

form, construction, arrangement, and combination of the several parts of my holder may be made and substituted for those herein shown and described without departing 35 from the nature and principle of my invention.

Having thus described my invention, what I claim and desire to secure by Letters Patent is;

In a holder for ties and the like, an approximately flat base, a pair of spaced apart side walls upstanding from said base and provided with alining downwardly and rearwardly disposed rack-slots, said base being longitudinally extended rearwardly and doubled upon itself at its rear end to provide a spring-tongue, said tongue projecting forwardly between said side walls and above said base and being yieldable vertically at 50 its free end relatively to the base, a bar extending transversely between said side walls and across said tongue, and projections on said bar fitting in said slots and adapted to engage the racks thereof for adjustably securing said tongue against yieldable movement upwardly from the base, said bar with its said projections being slidably movable relatively to said tongue.

In testimony whereof, I have signed my 60 name to this specification.

FISCHEL FISCHLOWITZ.
